UNITED STATES PATENT OFFICE

LOUIS C. HINDERER AND WALTER F. HINDERER, OF KANKAKEE, ILLINOIS

PUSH BUTTON WINDOW LOCK

Application filed September 10, 1930. Serial No. 438,998.

This invention relates generally to window locks for maintaining the window sashes locked in ventilating relation to the window frame, and particularly to a lock of this type which is operated into locking and released from locking position by pushing the same inwardly into the sash frame of one of the sashes in the manner of a push button, and turning the same to securely detain the lock in locking position.

It is an object of this invention to provide a device of the character described which comprises new and novel features of construction and arrangement, comprising a pair of mechanically cooperating horizontally slideable rods which are mounted in one side or upon either side of the vertical portion of the window sash or sashes, so as to, in released position, lock the sashes against movement in opposed directions, by projecting one of said rods to contact releasably the upper portion of one of the window sashes.

It is another important object of this invention to provide means in a lock of this type for detaining the locking means in locking position whereby the locking means may not be displaced from locking position by merely pressing or pushing the said means, said means comprising a structure associated with said locking means which is operated by turning the locking means to releasably engage a detent, and to disengage therefrom upon reversing the said turning.

It is also an object of this invention to provide a device of the character described which may be employed for preventing opposed motion or movement of two bodies in superimposed or side by side sliding relation, which may be operated easily and quickly, and does not in any manner interfere with the said relative movement when out of locking position.

It is also an object of this invention to provide a device of the character described, which is operable in the same manner as a push button, either of said pair of rods being projectable into or out of locking position by pressing inwardly upon either of them, and which is provided with mechanism for automatically ejecting one or other of said rods,

said mechanism being of new and improved arrangement and design, producing a superior operation especially adapted for a device of this character.

It is also an object of this invention to provide a suitable mounting and casing associated with said mounting, for suitably mounting the device in operating position in association with a window structure, or upon another structure embodying two relatively sliding members, which are required to be adjustably locked against relative movement with respect to each other.

It is also an object of this invention to provide a device of the character described which is especially adapted to releasably retain the window sashes in a window frame in predetermined ventilating relation with the window frame, providing ventilating openings either at the top or at the bottom or at both the top and bottom of the window frame, and to lock the sashes in said position, to prevent movement of the window sashes by a person on the outside of the window, and prevent such relative movement of the window sashes as would permit the sashes to be raised or lowered so as to admit an intruder.

It is also an object of this invention to provide a device of the character described which is simple and easy to operate, highly satisfactory when positioned as suggested, which is simple and easy and cheap to manufacture and which is admirably adapted for purposes for which it was designed.

These and other objects, the nature of the invention, its composition and arrangement and combination of parts will be readily understood by anyone acquainted with the art to which this invention relates upon consulting the following descriptions of the drawings, in which:—

Figure 1 is an elevational view of a window frame showing the mounting of my improved push button lock upon the sashes thereof.

Figure 2 is a side or edge view in fragment illustrating in detail the arrangement of the lock when in abutting position upon the upper end of a lower window sash.

Figure 3 is a front elevational view of the lock per se.

Figure 4 is a side elevational view of one modification of my improved lock in cross section on a vertical longitudinal line.

Figure 5 is an edge view of Figure 4 taken from the right.

Figure 6 is a detail of Figure 5 illustrating the back plate before installation as seen in Figure 5, and

Figure 7 is a partial vertical longitudinal section elevation of another modification of the structure shown in Figure 4.

It is to be understood that we do not desire to limit the application of this invention to the particular modification set forth herein to illustrate the principle thereof, and any change or changes may be made in material and structure consistent with the spirit and scope of the invention.

Referring in detail to the drawings the numeral 5 designates generally a window frame having slidable therein the upper window sash 6, and the lower window sash 7.

Positioned upon and mounted in one of the side members of the upper sash 6 and generally designated by the numeral 9 is illustrated our improved push button window lock, and referring to Figure 2 it will be seen that one of the rods of the lock is extended from the said sash 6 to abut the upper portion 8 of the sash 7 where an abutment plate 10 is provided for immediately contacting said rod. It is thought to be obvious that it will be understood that with the rod or bolt projected to abut the upper side of the abutment plate 10 fastened on the upper end of the lower window sash 7, that relative motion in the direction of the arrows in Figure 2 will be prevented. Obviously, the ventilation spaces 11 and 12 cannot under this arrangement be enlarged by a person attempting to shift the sashes from the outside of the window, or by a person unfamiliar with the operation of the lock from the inside. This arrangement, however, does not prevent the complete closing of the window whenever desired, either from the inside or from the outside of the window.

Referring to Figure 4 which is an illustration of a preferred embodiment of the principle of our invention, the numeral 13 designates the front or attaching plate of the lock structure, and as shown in Figure 3 it may be of any desired formation, preferably oval or rectangular, and provided with upper and lower extensions accommodating holes 14 which are formed to receive screws or other attaching means for securing the plate in position on its support. A pair of apertures 15 are formed in the central portion of the plate one over the other, to receive the forward end of a shoulder 16, on the forward ends of a pair of cylindrical casings 17 and 18. It is understood, of course, that

the casings 17 and 18 might be of any desired transverse section such as square, hexagonal, or any other desired shape. As indicated at 15 the forward ends of the apertures designated by the same number are slightly flared, to permit swedging the ends of the shoulder 16, for maintaining the casings 17 and 18 firmly united with the plate 13.

Referring to Figure 6, the oblong plate 19 which covers the rear end of the casings 17 and 18 is illustrated in detail. The plate 19 is secured against the rear end of the tubes 17 and 18 by prongs 20 which engage in notches 21 in the plate 19 against which they are then bent and pressed, to firmly unite the said plate against the rear ends of the casings 17 and 18. A pair of bosses 22 are provided on the inner side of the plate 19, projecting from a position on the said plate which may be set to be concentric with the inner walls of the casings 17 and 18. The bosses 22 have a purpose to be described hereinafter.

Snugly slidable in the upper casing 17 is the bolt or rod 23, which is adapted to have its outer end 24 flush with the plate 13 when pushed entirely into the casing 17. An intermediate portion of the periphery of the bolt 23 is provided with a groove 25, from the rear edge of which the bolt tapers gradually as at 26 to a point near the rear end of the bolt where is formed a flange 27 of the same diameter as the main portion of the bolt. A coil spring 28 is positioned at one end about the boss 22 and extends longitudinally into a cavity 29 formed in the rear end of the bolt 23, said spring adapted to normally urge said bolt into a position projecting from the casing 17. A pin 30 fixed in an intermediate position of the bolt 23 behind the groove 25 slides on the stop 40. When the pin reaches the forward end of the stop the bolt is turned to place the pin in the offset slot 40' for securely locking the bolt against inward movement.

Slidably and snugly fitted in the lower casing 18 is a plunger 30 whose forward part is similarly formed and positioned in retracted position to the bolt 23, and a spring 31 of the coiled variety is positioned upon the boss 22 within the casing 18, the forward end of the spring 31 being received in a recess 32 formed in the rear end of the plunger 30, which incidentally is somewhat shorter than the bolt 23. The cavity 29 is considerably longer than the recess 32. Provided in the lower walls of the casing 17 and the upper wall of the casing 18 so that they register, are a pair of elongated openings 33 which permit a pin 34 to be projected from the casing 18 into the casing 17 and to achieve registry with the groove 25 or the tapered portion 26 of the bolt 23. The pin 34 has an enlarged end portion 35 which is slidably mounted in a vertically disposed well 36 having the retaining

shoulders 37, to limit the complete projection of the pin 34. The pin 34 is normally projected through the opening 33 by a coiled spring 38 which exerts its force against the lower side of the casing 18 and the bottom surface of the enlarged portion 35 of the said pin.

The illustration in Figure 4 shows the mechanism in what is hereafter to be called the neutral position, such position being maintained by the projection of the pin 34 into the groove 25. Movement from this position is achieved by inward pressure upon the plunger 30 which results in disengagement of the pin 34 from the groove 25 permitting the spring 28 to project the bolt 23 into extended position. It is obvious that pressure upon the outer end 24 of the bolt 23 may result in once again registering the groove 25 upon the pin 34 and releasably locking the said bolt in neutral or retracted position.

A pin 50 is secured on the upper side of the bolt 23 and projects through the elongated slot 40 which terminates at its forward end in a right angular effect 40', so that as the bolt is ejected to locking position, a quarter turn will bring the pin 50 into the offset position of the slot and prevent opening the lock by using a stick or other pressure means from the outside of the window as might be attempted by an intruder.

A modification of the structure illustrated in Figure 4 and just described, is set out in Figure 7. In this modification in Figure 7 the general structure of the plate 13, the back plate 19 and the casings 17 and 18 and the bolt 23 and the plunger 30 are substantially identical in general formation, slight specific changes being made to accommodate the different moving parts of this modification. In this modification the bolt 23 is provided on its upper side with a projecting pin 39 near its rearward end and the pin 39 slides in an elongated slot 40, the pin 39 and the slot 40 providing for limiting the outward projection of the bolt 23. The pin 39 also functions like the pin 50 in the first described modification and locks the bolt by entering the offset 40' in the forward part of the slot 40. The bolt 23 is provided with the cavity 29 carrying the spring 28 positioned by a boss 22. A deep well 41 is provided leading from the lower side of the bolt 23 to a point almost to the opposite side, and within the well 41 is a coiled spring 42 downwardly urging a ball 43 which is adapted to be registered in an orifice 44 formed in the bottom side of the casing 17 in register with the open end of the well 41. This last named structure provides a releasable detent for maintaining the bolt 23 in neutral position. The push plunger 30 in this second modification, is of approximately the same relative length as the same element in the first described modification, but the bolt in the first modification is considerably

longer than the bolt in this second modification, the bolt and the plunger being of practically the same length in said second modification, for a reason which will be obvious from the description of the second modification. The plunger 30 is provided at its lower side at a central point thereof with a pin 45 which is registered in an oblong slot 46 in the lower side of the casing 18, said pin 45 and said slot 46 cooperating to limit the outward movement of the plunger 30 and to limit the movement inwardly when the same is pressed. Means to release the bolt 23 by pressure upon the plunger 30 is constructed as follows:

A pair of lateral projections indicated in dotted lines in Figure 7 at 47, are formed on the inner face of the plate 19 and they are transversely placed in the same plane and provide for supporting the ends of a shaft 48 journaled across the space between and in each of said projections, and centrally mounted upon said shaft 48 is a trigger 49 adapted to have one arm engaged with the rear face of the bolt 23, and have its other arm engaged with the rear face of the plunger 30, so that upon pressure being applied on the front end of the plunger 30, the trigger 49 will transmit the said pressure to the bolt 23 and cause the unseating of the ball 43 to permit the outward projection of the bolt 23 by the spring 28 to the limit of the slot 40 and retained by the pin 39. The operation and employment of our improved push button window lock is thought to be clear from the explanation and description already given above from which it will be evident that we have provided a device of the character described, which is mechanically efficient, which is easily and quickly and cheaply installed, and is otherwise admirably suited for the purpose for which it was designed.

What is claimed is:—

1. A window lock of the type described comprising a plate for mounting on a window structure, a pair of tubular casings secured at their front ends in apertures in said plate, and rearward plate closing the rearward ends of said casings and supporting them in relation to each other; and a bolt closely slidable in one of said casings and adapted to position its forward end flush with the plate, said bolt being formed centrally with a peripheral groove from which extends rearwardly a tapered portion, and a flange on the rearward end of the bolt; and a plunger closely slidable on the other of said tubular casings having a central vertical well, a pin and a spring for projecting the pin from said well, said pin adapted to be projected through registering apertures in said casings to seat frictionally in the said groove in said bolt; and a pair of bosses formed on the inner facing of said rearward plate, a coiled spring on each of said bosses and extended forwardly into

recesses in the rearward ends of said bolt and said plunger for maintaining them in operative position in the casings and projecting the said bolt to a position in extension from the said one casing, and means to lock the bolt against unauthorized inward movement.

2. A window lock of the type described comprising in combination, a window frame, window sashes slideable in the frame, a means for limiting the relative movement of said sashes in said frame, comprising a plate for mounting on a window structure, a pair of tubular casings secured at their front ends in apertures in said plate, and a rearward plate closing the rearward ends of said casings and supporting them in relation to each other; and a bolt closely slideable in one of said casings and adapted to position its forward end flush with the plate, said bolt being formed centrally with a peripheral groove from which extends rearwardly a tapered portion, and a flange on the rearward end of the bolt; and a plunger closely slideable in the other of said tubular casings having a central vertical well, a pin and a spring for projecting the pin from said well, said pin adapted to be projected through registering apertures in said casings to seat frictionally in the said groove in said bolt; and a pair of bosses formed on the inner facing of said rearward plate, a coiled spring on each of said bosses and extended forwardly into recesses on the rearward ends of said bolt and said plunger for maintaining them in operative position in the casings and projecting the said bolt to a position in extension from the said one casing.

40 In testimony whereof we affix our signatures.

LOUIS C. HINDERER.
WALTER F. HINDERER.
